UNITED STATES PATENT OFFICE.

FRANK A. FAHRENWALD, OF CLEVELAND HEIGHTS, OHIO.

RECUPERATIVE APPARATUS.

Application filed November 28, 1924. Serial No. 752,699.

This invention relates to the production and maintenance of high temperatures by the combustion of fuel as employed in the reduction, smelting, and refining of metals or the production and manipulation of glass, pottery, and other ceramic materials, the distillation of oils and oil shale, the production of power, and the performance of numerous chemical reactions requiring high temperatures. The combustion of fuel entails a constant supply of fresh air and an equivalent discharge of combustion products, the former entering at the prevailing seasonal temperature and the latter escaping often at the maximum temperature of the process. Sometimes the value-products of the operation are contained in the gases themselves as in distilling oil shale, sometimes the waste gases are largely valueless as in the chimneys of steam boilers and steel plants but in many cases the heat units carried by the escaping gas are sufficient to constitute the difference between a financially profitable and a financially unprofitable operation, and in all processes of commercial magnitude the saving of waste heat is both sound practice economically and lucrative financially.

Many attempts have been made to effect this economy, usually by inducing the escaping gases to give up some of their heat units to the entering air, thus decreasing the work necessary to be done by the action of fresh fuel but the practical difficulties are very great, especially considering the high temperatures and enormous volumes of gases often encountered.

Considering for example, a blast furnace of a size which requires for its operation approximately 50,000 cubic feet of air per minute (approximately two tons) delivered under a pressure of approximately ten inches of water. This air is delivered to the furnace by a pipe some three feet in internal diameter, at a temperature of from about 750° to 850° F. The hotter it is to start with, the less coke is required in the furnace. Each increase of 100° F. in the temperature of this air is equivalent to approximately three tons of coke per hour, and enables the saving of over 75 tons of coke a day. However, for reasons I shall soon point out it is not easy under present practice to maintain the temperature steadily even at 1000° F. The chemical operations in such a blast furnace result in the discharge of about 90,000 cubic feet per minute of a mixture of gases at from about 200° to 400° F. (the balance being employed in heating the ore, evaporating the water it contains and reducing the iron, which is a strongly endothermic process).

This blast furnace gas consists of approximately:

	Per cent.
Carbon monoxide	27
Carbon dioxide	12
Nitrogen	60
Hydrogen	1

The only valuable components are the carbon monoxide and hydrogen, which, even after being cooled to seasonal temperatures, have a combustion value equivalent to approximately 24 tons of coke per hour. After being cooled and washed about two-thirds of this gas is burned under boilers or in engines while the remaining one-third which is equivalent to about 8 tons of coke per hour is burned to preheat the air which is fed to the blast furnace. The present apparatus for effecting this is only about 50% efficient. Half the amount would do equally well if it could be thoroughly used, or the same amount would heat the entering air to a correspondingly higher temperature, thus saving coke in the furnace as first explained. It is for the particular purpose of saving a part of this 4 tons per hour loss that I have developed the particular devices hereinafter shown, although the same general apparatus can be applied to the saving of a considerable part of the waste heat contained in the blast furnace gas, and simple modifications of the apparatus equally falling within my invention can be utilized in other branches of the arts. Great as this saving is, it is even less important than the saving in overhead costs which can be effected by the consequent speeding up the action of the blast furnace, and the elimination of labor and superintendence costs.

In the establishing contemporary method each blast furnace is accompanied by four, upright, cylindrical, round topped regenerative stoves connected to the blast furnace, blower fans, waste stack, and each other by a maze of heat insulated piping and water cooled valves. Each stove is filled with a checkerwork pile of refractory brick except for a flue in which the blast furnace gas is burned, the products escaping to the waste stack after passing through the brick-work.

which is heated very hot. At the end of a given time the fire is shifted to the next stove in the series and air for the furnace is forced through the checkerwork which thus gives up its heat. During the first period of blowing each stove the air has to be diluted with cold air in order to maintain reasonably uniform conditions in the blast furnace. Toward the end of each blowing period the temperature of the stove falls so that no dilution is necessary and when the temperature falls to about 950° F. the blast is shifted to the next stove and the cold air valves again opened. It has never been considered feasible to run these stoves so as to afford an end temperature much above 1200° F. and even this is attained only with excessive waste as the heating and blowing have to be alternated more frequently and the minimum temperature of the escaping gases is correspondingly increased, thus decreasing the thermal efficiency even more severely. Moreover each stove costs between \$60,000.00 and \$100,000.00 and requires constant repairing, amounting in effect to triennial rebuilding. While the fourth stove is being repaired only three of the stoves are in operation.

Accordingly the detailed object of my present invention is the provision of recuperative apparatus for blast furnace or open hearth furnace use or by-product coke installation or the like which shall fit the interiors of these established regenerative stoves, operate with the same valves, blowers, pipes, and chimneys, compare favorably in cost with the present apparatus, require less repairing, economize a greater proportion of the heat, deliver air to the point of use at a higher temperature, and maintain that temperature more uniform. Another object is to enable a decrease in the number of stoves, by enabling each stove to be operated continuously, dispense with the need for diluting the effluent with cold air, and permit the abandonment of many of the valves, cross-connections and automatic temperature regulating devices heretofore used. Another object is to design the apparatus in such wise that commercially available metals can be used within their proper strengths under the different temperature conditions to which they are subjected, without anywhere employing unnecessarily expensive materials; also by increasing the speed of operation of the blast furnace to decrease the overhead costs and thereby effect the reduction at a lower price per pound; while further objects and advantages will become apparent as the description proceeds.

Two important principles of my invention are:

(a) The hot and cold gases must flow counter-currently adjacent the hot end of the ap-

paratus for protection of the mechanism and counter-currently adjacent the cold end for completeness of heat absorption;

(b) All metallic members which come in contact with hot gases must depend from a fixed connection at the top and be free to move at the bottom since the only available metals have a greater tensile strength at high temperatures than they have rigidity of form;

A corollary of these principles is:

(c) The air or gas being heated should flow vertically in an unbroken direction, while the waste gases should have a broken path, first upward and then downward (or vice versa).

The first of these principles constitutes the essential subject-matter of my copending application filed March 2, 1921, Serial No. 449,172. The present application constitutes an improvement thereon in respect of certain features connected with the practical large scale employment of that principle.

In the drawings accompanying and forming a part of this application I have illustrated certain typical embodiments of my invention as applied to blast furnace regenerative stoves. Fig. 1 is a central vertical sectional view through such a stove containing my improvements, together with its exhaust flue or chimney; Fig. 2 is a vertical central sectional view of the upper part of a similar stove equipped with a slightly modified form of my apparatus; Fig. 3 is a vertical central sectional view of the bottom part of a stove showing another slightly modified detail of my invention; Fig. 4 is a horizontal sectional view corresponding to the line 4—4 of Fig. 3; Fig. 5 is a central vertical sectional view through the upper part of another blast furnace stove showing another detail modification; Figs. 6, 7, 8, and 9 are detail views of the lower ends of the heat transfer pipes and the mode of connecting same to the manifolds; Fig. 10 is a horizontal sectional view corresponding to the line 10—10 of Fig. 1; Fig. 11 is a horizontal sectional view corresponding to the line 11—11 of Fig. 5; Fig. 12 illustrates another mode of supporting and arranging the heat transfer pipes; and Fig. 13 is a horizontal sectional view of yet another arrangement of stove interior.

Describing the parts by reference characters, 1 denotes the exterior shell or casing of a standard blast furnace regenerative stove which is generally cylindrical in shape with a diameter of approximately 22 ft. and a height of approximately 100 ft. Its upper end is surmounted generally by a curved cap 2 and its entire interior is lined with refractory brick 3 from eighteen inches to three feet in thickness.

Inside the cylindrical chamber thus defined I erect a vertical cylindrical chimne

indicated at 4 in Fig. 1 and defining an exterior annular, down-draft chamber 5 and an internal cylindrical updraft chamber 6. In the bottom of the chamber 6 are located 5 the provisions for burning the blast furnace gas, shown as comprising an upright pipe 7 communicating with the conduit 8 by which the gas is conveyed to the apparatus, and an air pipe 9 located inside the 10 pipe 7 and communicating with the blower 10 by which air is delivered to consume this gas. Near its lower end the stove is encircled by a horizontal flue 11 communicating with the chamber 5 by angularly spaced 15 passages 12—12 for the escape of waste products, the flue 11 communicating with the exhaust fan 13 which may conveniently discharge into the waste stack 14 generally provided near these stoves and often of considerable height. Preferably the chimney 4 extends to comparatively near the top of the stove. I do not limit myself to the use of an exhaust fan since the pressure under which the air and gas are injected is often adequate 25 for their ejection but the low and uniform temperature of the waste gases permits the use of common steel blowers at 13 and the requisite draft can be obtained much more cheaply by the use of mechanical applications than by natural draft. Besides this permits the abstraction of even more heat from the waste gases as will be shown. Such an exhaust fan is particularly useful when my improved recuperative stoves are used 30 in connection with open hearth furnaces.

Adjacent to the top of the stove I locate a suitable manifold which in this particular installation serves the double purpose of collecting the heated air and supporting the 40 pipes in which it is heated. In the form shown in Fig. 1 this manifold is shown at 15 and is annular in shape, its outer diameter being greater than the exterior diameter of the chimney 4 and its internal diameter 45 being less than the internal diameter of the chimney 4. This manifold communicates with a branched discharge pipe 16 which in turn communicates with a suitable conduit 17 here shown as emerging from the top of the stove and leading thence downwardly and laterally to the blast furnace (not shown). Formed in the upper surface of the manifold 15 are a plurality of angularly spaced apertures 18 each preferably flaring upwardly as shown in Fig. 1 and receiving the correspondingly tapered downturned ends of goose-necks 19 formed at the upper ends of pipes 20 which depend vertically into the chamber 5 and other 50 pipes 21 which depend into the chamber 6. The manifold is supported in place in any suitable or desired manner. In Fig. 1 I have shown it as resting on an arch 24 of refractory brick built in the upper end of the 55 stove, this arch being formed with suitable

apertures 25 for the passage of the different pipes. Such an arch is preferably employed in any case in order to shield the manifold and the upper ends of the pipes from the direct contact of the hot gas, although its supporting function can be more or less delegated to other devices as will hereafter be shown. The manifold 15, pipe 16, pipes 21, and at least the upper ends of pipes 20 are made of alloys of chromium 70 preferably containing approximately:

Chromium between 14% and 18%.
Nickel between 30% and 38%.

Silicon between 1% and 2%, and the balance chiefly iron; although it is of course 80 possible to omit some or all of the silicon and substantially vary the proportions of chromium, nickel, and iron, although the alloys made within the range described exhibit a greatly increased strength at high temperatures which is the most difficult quality to secure in apparatus of this character. However, by employing the features of invention which I have set forth herein it becomes possible to use some of the other 90 alloys of chromium with iron group metals which would otherwise be too weak for use. For example, while the alloy first described, 95 is highly resistant to oxidation it is not so immune to highly sulphurous gases and certain metallic fumes as are some of the other chromium alloys such as Cr 25 Fe 75, which, however, are comparatively weak at high temperatures.

The lower ends of these pipes are connected to suitable manifolds, preferably at points well below the outlets 12 and burner 7; the outer manifold is shown at 26 and the inner manifold at 27, both being connected by means of a branched pipe 28 with a blower 29 by which air is supplied. The pipe 28 preferably has an internal diameter of between three and four feet and the blower must be able to deliver at least about 50,000 cubic feet of air per minute. If it is desired to heat this air to a temperature of 1200° F. for delivery to the blast furnace it is necessary to afford approximately 20,000 square feet of heat transferring surface, in contact with the hot gases, it being assumed that the temperature of the chamber 6 at the mouth of the burner 7 is approximately 2600° F. and the temperature at the flues 12 is approximately 200° F. If the issuing air is to be heated to a lower temperature, or the escaping waste gases are discharged at a higher temperature a smaller amount of heat transferring surface can obviously be employed. Assuming that each pipe makes contact with the heated 115 gases for 50 feet of its length, this requires approximately 270 six inch pipes or 400 four inch pipes, either of which numbers is very easily accommodated inside the space provided. Owing to the small scale of the 120 130

drawings it has been possible only to indicate in a general way the locations of these pipes and the dimensions of the various chambers and no attempt has been made to 5 illustrate the actual arrangement of the parts or the relative numbers of pipes in the two main chambers.

These pipes may be connected to the manifolds in any one of many different ways, 10 a few of which are illustrated in Figs. 6, 7, and 8. In Fig. 6 the manifold 27 is supported by a saddle 30 and is formed opposite each of the tubes 21 with an annular pocket 31 containing mercury or other 15 liquid, thus sealing the joint while permitting expansion and contraction of the parts which amounts to about six inches between extreme temperatures. Another mode is shown in Fig. 7 wherein the manifold 27^a 20 likewise rests on a saddle 30 but instead of a mercury seal is formed with a packing gland 32 engaging a soft packing 33 which engage the pipe 21 slidably, thus producing a sliding joint. In Fig. 8 the manifold 27^b 25 is provided at one side with a packing gland 34 adapted for the reception of hard packing 35 tightly gripping the pipe so that the manifold is supported out of contact with the ground by the joint action of all 30 the pipes and rises and falls therewith.

In Fig. 9 the manifold 27^c is formed with nipples connected to the pipes by flexible hose which can even be of canvas when the temperature of the entering air is low. In 35 the form of the device shown in Fig. 1 the lower ends of the chambers 5 and 6 are separated from the upper portions of the same by suitable arches 36, and never reach any elevated temperature. If cold air be forced 40 into the pipe 28 these chambers are cool at all times. The pipes 21 become very hot inside the chimney 4 although the concurrent direction of flow protects them from becoming overheated and quickly reduces 45 the temperature of the burning gases to a point where they are no longer harmful to the brick work. By the time these gases come in contact with the arch 24 and pipes 20 they are generally cooled at least to 50 about 1200°-1400° F. Only the upper ends of the pipes 20 need ordinarily to be of heat resistant material since common iron or 55 steel materials are generally satisfactory for the lower ends thereof. The best design 60 is that wherein the air enters the manifold 15 at the desired temperature from both sets of pipes, although this requires a very much greater number of pipes in the chamber 5 than in the chamber 6, and it is practically satisfactory if the mixture of the 65 two gases possess the proper temperature, the waste gas escaping through the flues 12 being reduced to a sufficiently low temperature, and sufficient air at the same time introduced by way of the pipes 21 to protect

the latter against overheating. Owing to the fact that the hottest parts of all the pipes depend vertically from supports at their upper ends, the apparatus exhibits a minimum tendency to deformation. 70

The heated air issuing from this stove exhibits a constant temperature and the temperature of the waste gases likewise remains constant and comparatively low degree, though seldom below 200° to 300° F. Accordingly it becomes possible still further to extract some of this heat if desired since the temperatures are so low that metals of the cheapest nature can be successfully used for the purpose, and the gases carry very 80 little dust or corrosive substances. One arrangement for effecting this is shown at the right of Fig. 1 wherein the lower part of the chimney 14 is filled with economizer units, each consisting of a pair of hollow 85 sheet iron headers 40-40 connected by sheet iron cross pipes 41, which may be common stove pipe so far as the severity of the use is concerned. These can be connected inside the chimney in any suitable 90 manner to afford the necessary rate of flow, air being admitted at any suitable point by the inlet 42, and in this manner the flue gases cooled an additional 100°, which is equivalent to nearly two tons of coke per 95 day. This saving merely requires the economizers to be attached to the intake of the fan 29 and also preferably of the fan 10.

In Fig. 2 I have shown another mode of supporting and arranging the pipes. The upper end of the chimney 4 is formed with laterally opening apertures 4^a thus allowing the manifold to be set on top of the chimney. The manifold here shown consists of a cylindrical central section or hub, having 105 a flat bottom 45 and cylindrical side walls from which radiate the hollow arms 47. The pipes 20 and 21 depend from the bottom walls of the hub and arms, being flared inside the same as in boiler making. A 110 manhole 48 permits the entrance of a workman. Obviously this manifold could be supported above an arch if desired, although this form of attachment is rather best suited of any for direct contact with 115 the hot gases and the manifold constitutes a further heating surface.

In Fig. 3 I have shown a modified arrangement of inlet and outlet flues. The shell 1, lining 3, chimney 4 and chambers 120 5-6 appear as before but the gas inlet passage 8^a is elevated to a greater height while the gas outlet passage 12^a is lowered to ground level. The bottom of the chimney is traversed by an arch 36 which separates 125 the incoming and outgoing gas streams, defining a shallow chamber underneath, the thrust of this arch being supported by narrow radial arches or flying buttresses 50 which traverse the chamber 5 but without 130

closing passage through the same. The lower end of the chimney 4 is formed with arch ways 51 establishing communication between all parts of the bottom of the stove.

- 5 Secured to the lower ends of the tubes 20-20 is an annular manifold 26^a which, when the tubes are staggered as herein shown, is preferably made flatter and wider than shown in Fig. 1, and also because of 10 the fact that this manifold lies in the path of the escaping gases, is preferably secured tightly to the pipes as indicated in Fig. 8 owing to the heat to which it is subjected which would likely injure any slip joint. 15 The manifold 27^a is preferably secured to the pipes 21-21 in the same manner and when these pipes also are staggered it is similarly made of flattened section.

The constructions heretofore shown require the discharge of the heated air at the top of the stove which is practically feasible though sometimes inconvenient. To cover the latter class of cases I have in Figs. 5, 10, and 12 illustrated devices in which provision is made for the return movement of the heated air inside the stove itself. In Fig. 5 the chimney 4^b is made with vertical passageways 54 therein extending throughout its whole height; or the chimney may be considered as made of two concentric walls spaced apart which is another way of saying the same thing. Located at the upper end of the stove is a manifold 15^a having secured thereto pipes 20 and 21 as described 25 in connection with Fig. 1. I have shown this manifold as shielded from the direct action of the hot gases by means of a fire brick arch 24^a, although in the present instance this arch is relieved from all supporting function, the manifold being sustained by suitable suspending provisions 55 suitably connected to a frame work 56 located outside of the heated area.

Secured to the bottom wall of the manifold 15 are a plurality of depending vertical discharge pipes 57 which pass through the passageways 54 to any suitable outlet provision (not shown) at the base of the stove. The entire pipe 21 requires to be 45 made of heat resistant alloy, and also the upper ends of the pipes 20 and 57. In case the temperature of the air delivered by the stove is not over 900°-1000° F. it is often 50 possible to make these pipes of a cheaper material beginning at some point below the top of the chimney 4^b, especially the pipes 20^a which depend into a region of gradually decreasing temperature. The pipes 57^a however, retain a substantially uniform 55 temperature between the increasing temperature on the inside and the decreasing temperature on the outside. It should be remembered, however, that ordinary steel exhibits at 60 1000° F. only approximately one-fifth the tensile strength it has at room temperature,

while the special alloy first hereinbefore defined retains a working strength of about 10,000 lbs. per square inch at this temperature and 4000 lbs. per square inch at 1400° F. while steel cannot be subjected to any appreciable continuous stress at the last named temperature.

In Fig. 13 I have shown another arrangement for returning the heated gases wherein in the chimney is made in the form of two concentric cylindrical shells 4^c and 4^d spaced apart to define an annular combustion chamber 6^c. Inside the innermost shell is located a vertical downdraft pipe 17^c through which the heated air is withdrawn while the heat transfer pipes 21 continue to occupy the annular chamber 6^c and the pipes 20 the outside annular chamber 5^c. The pipe 17^c should be made of heat resistant metal throughout; furthermore this pipe exhibits a certain degree of absorbing function throughout since the chimney shell which surrounds it is more highly heated at all times than the air inside this pipe.

In Fig. 12 I have shown another arrangement for supporting the different pipes wherein 60 represents a chamber substantially like that shown in Fig. 2 and 61 represents hollow arms of heat resistant metal projecting therefrom and formed at their outer ends with spaced radiating fingers 62. Each of these fingers is formed on its upper surface with a plurality of holes in which the goose-necks are seated.

In practice the depending pipes can be made of fairly thin metal and it is found that the total weight of the interior parts of the stove is substantially less than when the same is constructed in the usual manner. Each stove constructed in this way costs but little if any more than the construction usually employed and is capable of being used almost indefinitely. In order to provide for inspection and repair I advocate making these stoves in pairs, or, when they are built by remodeling the existing type of gas furnace regenerative stove, I advocate using only the two stoves which are nearest to the chimney for this particular purpose, either abandoning the remaining stoves or turning them to other purposes such as recovering a part of the heat from the blast furnace gases. It will be understood, however, that I do not limit myself to the construction of my improved economizers in abandoned regenerative stoves since even better results can be achieved with specially designed devices.

I have shown the parts inside the casing as symmetrically arranged since this is most conducive to equality of heat expansion and is most convenient with a circular chamber, but I do not confine myself to circular chambers nor to a symmetrical arrangement. Neither do I in all cases limit myself to an

arrangement of the pipes in vertical position, nor to an arrangement of the pipes parallel to the flow of the hot gases, although under the extreme conditions met in the specific use herein described these arrangements have large practical advantages. Also I have shown the vertical wall which separates the updraft and downdraft chambers as circular in shape constituting a chimney, but it will be obvious that a separation into chambers could be effected with different configurations of walls. Accordingly I do not limit myself to any detail of design, arrangement, construction, material, or other feature except as specifically recited in my several claims which I desire may be construed each independently of limitations contained in other claims.

Having thus described my invention what I claim is:

1. Preheating or recuperative apparatus for gases comprising a pair of hollow upright chambers communicating at their upper ends, means for delivering heated gases to the bottom of one chamber and discharging such gases from the bottom of the other chamber, upwardly extending conduits of heat-conducting material located in both chambers, and means for causing an upward flow through all said conduits of the gases to be heated.

2. Preheating or recuperative apparatus for gases comprising a pair of hollow upright chambers communicating at one end, means for delivering heated gases to the non-communicating end of one chamber and withdrawing the same from the non-communicating end of the other chamber, longitudinally extending conduits of heat conducting material in both chambers, and means for causing the gas to be heated to flow through such conduits in the same direction with the heated gases in the hotter chamber and in an opposite direction from such gases in the cooler chamber.

3. Preheating or recuperative apparatus for gases comprising an upright chamber, vertically disposed conduits of heat conducting material suspended in said chamber, a manifold connected to the lower ends of said conduits, said manifold having a gas connection adjacent to the lower end of said chamber, means for causing hot gases to flow lengthwise of said chamber outside of said conduits, and means for causing gases to be heated to flow through said conduits.

4. Preheating or recuperative apparatus for gases comprising a pair of elongated parallel chambers for heated gases communicating with each other at one end, means delivering heated gases to the non-communicating end of one chamber and withdrawing such gases from the non-communicating end of the other chamber, longitudinally extending conduits of heat conducting material

located in both chambers, means for causing the gases to be heated to flow through all said conduits and means for mixing together those gases which flow through the conduits located in the respective chambers, the direction of flow being concurrently with the heated gases in the hotter chamber and opposite to the flow of the heated gases in the cooler chamber.

5. Preheating or recuperative apparatus for gases comprising a hollow vertical heat resistant shell, an upright chimney in said shell and defining chambers inside and outside the same, means for delivering heated gases to the bottom of one chamber and discharging such gases from the bottom of the other chamber, upwardly extending conduits of heat conducting material located in both chambers, and means for causing an upward flow through all said conduits of the gases to be heated.

6. Preheating or recuperative apparatus for gases comprising a hollow vertical heat resistant shell, an upright wall in said shell and defining therewith an updraft chamber and a downdraft chamber, means for heating the lower end of one chamber, means for discharging spent products from the lower end of the other chamber, a plurality of metal pipes suspended at their upper ends and depending vertically into said chambers, means for introducing gases to be heated into the lower ends of all said pipes, and means for carrying away the heated gases from the upper ends of said pipes.

7. Preheating or recuperative apparatus for gases comprising a hollow vertical heat resistant shell, a vertical chimney in said shell and spaced from the walls thereof, means for introducing combustible material to the bottom of said chimney, means for discharging spent combustion products from the lower end of said shell, the interior of said chimney communicating with the chamber surrounding the same only at the top, a hollow manifold of heat resistant material located above the top of said chimney, metal pipes depending from said manifold both into said chimney and into the chamber surrounding said chimney, manifolds connected to the lower ends of said pipes, means for delivering the gases to be heated to said last manifolds and means for conveying away the heated gases from said first manifold.

8. Recuperative apparatus adapted for introduction into existing blast furnace stoves comprising a vertical chimney of refractory material extending from the bottom thereof to a point near its top and spaced from its wall to define an annular chamber, the interior of the flue constituting a combustion chamber and the exterior a downdraft chamber, a manifold of heat resistant metal supported above the top of

- said chimney, other manifolds located at the bottoms of said chambers, vertical metal pipes connecting said first manifold to both said second manifolds, means for discharging spent gases from the bottom of the downdraft chamber, means for forcing air to be heated into the bottom manifolds, and means for conveying the heated gases away from the top manifold.
- 10 9. Recuperative apparatus comprising, in combination, a gas combustion chamber, a chamber through which the combustion products are passed, means including conduits of heat conducting material located in said chambers and a pump connected to said conduits in forcing relation for reducing the temperature of said products below red heat, a third chamber through which the combustion products pass, and other conduits of heat conducting metal located in said last chamber and connected to the intake of said pump for abstracting further heat units from said combustion products.
- 15 10. The combination with a blast furnace stove and its chimney, said stove comprising a hollow shell lined with refractory material and said chimney being connected to said shell near its lower end, of a chimney of refractory material rising inside said shell to a point near its upper end and constituting a combustion chamber, means for introducing combustible gas into the lower end of said last chimney, the space around said last chimney constituting a down draft chamber, metallic conduits in said chambers, and pump means for forcing air upwardly through all said conduits.
- 20 11. The combination with a blast furnace stove and its chimney, said stove comprising a hollow shell lined with refractory material and said chimney being connected to said shell near its lower end, of a chimney of refractory material rising inside said shell to a point near its upper end and constituting a combustion chamber, means for introducing combustible gas into the lower end of said last chimney, the space around said last chimney constituting a down draft chamber, metallic conduits in said chambers, pump means for forcing air upwardly through all said conduits, other conduits of sheet metal in said first chimney, and connections between said last conduits and the intake of said pump means.
- 25 12. In recuperative apparatus, a chambered structure constituting an updraft passage and a downdraft passage for gases from a furnace, a plurality of vertical conduits of heat conducting material located in both passages for the gases to be heated, means for forcing gases to be heated in an upward direction through all of said conduits, means for mixing all such last named gases after passing through their respective conduits and a mechanical exhaust device connected to said downdraft passage.
- 30 13. In recuperative apparatus, a refractory walled chamber constituting a passageway for combustion products, metallic conduits therein for the gases to be heated arranged and adapted to reduce the temperature of the waste gases below red heat, a mechanical exhaust device connected to the outlet from said chamber, a discharge chamber into which said exhaust device delivers, metallic heat-transfer pipes in said last chamber, and a pumping device having its intake connected to said last pipes and its outlet connected to said metallic conduits.
- 35 14. Preheating or recuperative apparatus for gases, comprising a hollow upright heat resistant shell and a plurality of metal pipes suspended from their upper ends and depending from their upper ends and depending vertically inside said shell, a discharge manifold communicating with the upper ends of said pipes, and flexible supply connections for the lower ends of said pipes, said connections extending out through the lower portion of said shell.
- 40 15. The method of preheating air by heat interchange with hot combustion products which is characterized by subjecting a portion of the coldest air to the action of the hottest portion of the combustion products whereby the apparatus is shielded from injury, and subjecting the remaining portion of the coldest air to the action of the coolest portions of the combustion products whereby the maximum amount of heat is abstracted therefrom, and subsequently mixing the two portions of air.
- 45 16. Recuperative apparatus for industrial high temperature uses comprising chambers for the heated waste gases, conduits of heat conducting material for the gases to be heated suspended vertically in said chambers, power exhaust apparatus for such waste gases, and power pumping apparatus for the gases to be heated, the flow of the gases to be heated being arranged to cool said conduits so as both to protect the same from the heat of the waste gases and also to cool such waste gases sufficiently to shield said exhaust apparatus from injury.
- 50 17. Recuperative apparatus for blast furnaces comprising conduits of heat conducting material located inside the chamber of the existing type of blast furnace regenerative oven, and means for forcing air to be warmed through said conduits whereby the same is heated to a temperature greater than 1000° Fahrenheit and the conduits themselves protected against injury.
- 55 In testimony whereof, I hereunto affix my signature.

FRANK A. FAHRENWALD.
